CLAIM

(58) **Field of Classification Search**

The ornamental design for a well of assay plate as shown and described.

USPC D24/128, 216, 223–230; D3/203.1,
 D3/203.3; D19/75, 85, 90CPC A61B 5/150343; B01D 9/00; B01L 3/06;
 B01L 3/502; B01L 3/5025; B01L 3/5082;
 B01L 3/5085

See application file for complete search history.

DESCRIPTION

(56) **References Cited**

2. Well of assay plate

2.1 : Perspective

2.2 : Perspective

2.3 : Top

2.4 : Back

2.5 : Right

2.6 : Front

2.7 : Left

2.8 : Bottom

2.9: Cross sectional

2.10 : Cross sectional

Design 2: well of assay plate, the well having a special profile.
